[57] CLAIM

The ornamental design for a tool pocket for the storage of tools in a machine tool assembly, as shown and described.

DESCRIPTION

FIG. 1 is a right side elevational view of a tool pocket for the storage of tools in a machine tool assembly showing our new design;

FIG. 2 is a front elevational view thereof;

FIG. 3 is a rear elevational view thereof;

FIG. 4 is a left side elevational view thereof;
FIG. 5 is a vertical cross-sectional view thereof, taken in the direction of line 5—5 of FIG. 2;

FIG. 6 is a top plan view thereof;

FIG. 7 is a bottom plan view thereof;

FIG. 8 is a fragmentary cross-sectional view thereof, taken along line 8—8 of FIG. 2;

FIG. 9 is a fragmentary cross-sectional view thereof, taken along line 9—9 of FIG. 3;

FIG. 10 is a bottom, front, and left side perspective view thereof; and,

FIG. 11 is a bottom, rear; and left side perspective view thereof.
